UNITED STATES PATENT OFFICE

GUY P. DREWETT, OF CHICAGO, ILLINOIS, ASSIGNOR OF ONE-HALF TO RICHARD M. HOFFMAN, OF CHICAGO, ILLINOIS

DESIGN FOR A STAND OR HOLDER

Application filed December 30, 1931. Serial No. 42,316. Term of patent 7 years.

To all whom it may concern:

Be it known that I, GUY P. DREWETT, a citizen of the United States, and a resident of the city of Chicago, in the county of Cook and State of Illinois, have invented a new, original, and ornamental Design for a Stand or Holder, of which the following is a specification, reference being had to the accompanying drawings, forming a part hereof.

This ornamental design for a stand or holder may be used for an incense burner, ash tray, urn, toy bank, lamp, candelabra, fountain pen holder, ink well, or any other similar article.

In the drawings:

I claim:

The ornamental design for a stand or holder, as shown and described.

GUY P. DREWETT.
